RAILWAY TRAFFIC CONTROLLING APPARATUS FOR INTERLOCKED HOME SIGNALS

John R. Myers, New York, N. Y., assignor to The Union Switch and Signal Company, Swissvale, Pa., a corporation of Pennsylvania

Application July 2, 1946, Serial No. 680,924

5 Claims. (Cl. 246—26)

1

My invention relates to railway traffic controlling apparatus, and more particularly, to apparatus for the control of interlocked home signals in a block signaling system of the overlap type including automatic train stops.

In signaling systems of this character, it is the practice to employ neutral "home" and "distant" relays for the control of the caution and proceed aspects of the signals, and to provide an additional relay for the control of the "call-on" aspect provided in connection with an interlocked home signal to permit a train to pass the signal when the track section in advance is occupied.

One object of my invention is to eliminate this additional relay, and to provide a system employing only one relay for controlling both the proceed aspect and the call-on aspect of the signal, but without causing undesired flashing of any of the signal lamps during a change from one aspect to another.

I shall describe one form of apparatus embodying my invention, and shall then point out the novel features thereof in claims.

In the accompanying drawing, I have shown a track plan of a stretch of railway track containing a small interlocking plant comprising a track switch 1 and an interlocked home signal 2 for governing traffic movements over the switch, together with the circuits and apparatus arranged in accordance with my invention for controlling signal 2 and a mechanism 2V associated therewith for operating the trackway tripping member 2a of an automatic train stop. As shown, the tracks are divided into block sections 1T, 2T, etc., each equipped with a track circuit having a track relay 1TR, 2TR, etc., normally energized by alternating current from a source the supply terminals of which are identified by the reference characters BX and CX.

To simplify the drawing the local source of current for energizing the various relays is identified by its terminals which are designated B and C, respectively.

Since they form no part of my invention, the circuits for controlling the track switch 1 are not shown, but the position and locked condition of the switch is reflected in the signal circuits by the provision of a normal switch indication relay 1NWP and a reverse switch indication relay 1RWP, each of which when energized manifests that the switch is closed and locked in a corresponding normal or reverse position.

Signal 2 is of the color light type comprising an upper signal unit 2A containing three lamps G, Y and R and an illuminated number plate dis-

2

playing the signal number. These lamps are controlled in accordance with traffic conditions by a home signal relay 2H and a distant signal relay 2D and also by a repeating relay 2VP of the train stop mechanism 2V. The lamps G, Y and R of a similar signal unit 2B are controlled by relays 2H and 2VP and also by relays 1NWP and 1RWP to designate the route governed by signal 2. A third signal unit 2C has a single lamp Y which serves as a call-on signal and is controlled by relay 2D and by a manually controllable stick relay 2COS. The home relay 2H is controlled by a manually operable signal lever 2SG and by a stick relay 2HY controlled by the track relays 1TR and 4TR when switch 1 is normal or by relays 1TR and 6TR when switch 1 is reversed, sections 1T and 4T or 6T embracing the home control limits for signal 2. When relay 2H is energized relay 2D extends the control limits for signal 2 to include one or more sections beyond the next signal 4 or 6 in advance in the route established by switch 1, the circuits for relay 2D including front contacts of relays 4H and 4VP when switch 1 is normal and the corresponding contacts of relays 6H and 6VP when switch 1 is reversed. It is to be understood that these relays are controlled by track relays like relays 2H and 2VP, except that no lever control is provided and they are normally energized. The operation of relay 2D as a distant relay is not needed when relay 2H is released, and relay 2D is then enabled to serve as a call-on signal relay to control lamp Y of the lower signal unit 2C, in accordance with a feature of my invention. The operation of the apparatus of my invention under different assumed conditions will now be described in detail. Assuming that switch 1 is normal, as shown, relay 2HY is energized over the circuit from terminal B at contact a of relay 1NWP extending over contacts a of relays 4TR and 1TR through relay 2HY to terminal C at the normally closed contact a of lever 2SG or at the front contact a of relay 2HY. If now the operator reverses lever 2SG, relay 2HY is held energized over the stick circuit including its contact a and relay 2H picks up over the circuit from terminal B at contact b of lever 2SG, back contact a of relay 2COS, contacts b of relay 2HY and mechanism 2V through relay 2H to terminal C, relay 2H completing a stick circuit at its own front contact a. Relay 2H completes a circuit at its contact b to energize mechanism 2V, which retracts the trip arm 2a and energizes its repeating relay 2VP. Relay 2VP then completes a circuit from terminal BX of the alternat-

ing current source over its front contact *a*, front contact *c* of relay 2H and back contact *a* of relay 2D through lamp Y of signal 2A to terminal CX of the same source, and also completes a branch circuit over contact *b* of relay 1NWP through lamp G of signal 2B, causing these lamps to become lighted and the signal lamps R to be extinguished. The indication displayed by signal 2 will therefore change from stop to caution to authorize a train to advance to signal 4, and if signal 4 indicates caution or proceed, relays 4H and 4VP will be energized to complete a circuit from terminal B over their front contacts *a*, contact *c* of relay 1NWP, front contact *d* of relay 2H, through relay 2D to terminal C, relay 2D becoming energized to light lamp G of signal 2A in place of lamp Y to change the indication displayed by signal 2 from caution to proceed.

If now a train in section 2T enters section 1T, relays 1TR, 2HY, 2H and 2D release, restoring signal 2 to stop, but mechanism 2V will be held energized by a retaining circuit including front contact *b* of relay 2VP, and back contacts *b* of relays 1TR and 2TR, until the entire train has passed the trip arm 2a, whereupon mechanism 2V and relay 2VP will be released by the opening of back contact *b* of relay 2TR to restore arm 2a to its operative position.

To clear signal 2 for a following train, after sections 1T and 4T are vacated, lever 2SG must first be restored to normal to pick up relay 2HY over the lever contact *a*, and mechanism 2V must be released to close its contact *b* in the pick-up circuit for relay 2H.

Assuming next that it is desired to pass a following train from section 2T to section 1T at slow speed, before section 1T or 4T is vacated. Since relay 2HY is held released, relays 2H and 2D do not pick up when lever 2SG is reversed. The operator presses the call-on push button 2CO, and since relay 2TR has been released by the approaching train, this completes a circuit from terminal B at back contact *b* of relay 2D over back contact *e* of relay 2H, contact *a* of button 2CO and contact *c* of lever 2SG through relay 2COS to terminal C at back contact *a* of relay 2TR, so that relay 2COS picks up completing a stick circuit at its own front contact *a* extending to terminal B at contact *b* of lever 2SG.

Relay 2D then becomes energized over the circuit from terminal B at contact *d* of relay 1NWP, contact *b* of relay 2COS, back contact *d* of relay 2H through relay 2D to terminal C, and relay 2D completes a circuit over its contact *c* and contact *c* of relay 2COS to light lamp Y of the call-on signal 2C, lamps R of signals 2A and 2B also being lighted.

The trip arm 2a remains in its operative position, since relay 2H has not been energized, but may be retracted by the operation of a key or push button PB by the train crew, thereby completing a circuit over contact *d* of relay 2D to energize mechanism 2V. Relay 2VP then picks up and its contact *b* completes a stick circuit for mechanism 2V extending to terminal B at contact *e* of relay 2D so that mechanism 2V remains energized after button PB is released. The lamps R are now lighted over front contact *a* of relay 2VP and back contact *c* of relay 2H.

It will be seen that as the train passes the call-on signal and vacates section 2T, the opening of back contact *a* of relay 2TR releases relays 2COS and 2D, and since back contact *b* of relay 2TR is also open, relay 2D releases mechanism

2V and relay 2VP, and if lever 2SG is placed in its normal position, relay 2HY will become energized when the train vacates sections 1T and 4T to restore the apparatus to the condition shown in the drawing.

- When switch 1 is reversed so that relay 1RWP is energized in place of relay 1NWP, the operation of the system is similar to that already described with the exception that lamp Y of signal 2B will be lighted in place of lamp G of that signal, to designate that the diverging route is established and a detailed description of the operation of the system under this condition is deemed unnecessary.
15. It will be seen that lamp Y of signal 2C is not lighted when relay 2D is picked up by the operation of relay 2H because relay 2H can pick up only when relay 2COS is released to open the lamp circuit. Lamp Y of signal 2A does not flash 20 when the signal aspect changes from proceed to stop because the release of relay 2D follows that of relay 2H. Temporarily, that is, for the release period of relay 2D, relay 2D is picked up with relay 2H released, as required for the display of 25 the call-on signal 2C, but lamp Y of signal 2C does not flash because relay 2COS cannot be picked up to complete the lamp circuit until back contact *b* of relay 2D closes.

Although I have herein shown and described 30 only one form of apparatus embodying my invention, it is understood that various changes and modifications may be made therein within the scope of the appended claims without departing from the spirit and scope of my invention.

35. Having thus described my invention, what I claim is:

1. Railway traffic controlling apparatus comprising a railway signal adapted to display stop, caution and proceed indications and to also display a call-on indication, a home relay controlled by traffic conditions and a distant relay controlled over a front contact of said home relay by other traffic conditions for controlling said signal, circuits controlled by the home relay for changing the indication of said signal from stop to caution when the home relay is energized and to proceed when the distant relay is also energized, a manually controllable stick relay having a pick-up circuit arranged to be closed only when the home and distant relays are released and a stick circuit independent thereof, circuits controlled by said stick relay when picked up for energizing said distant relay while maintaining said home relay released, and means for causing the display of said call-on indication when said distant relay is energized by the operation of said stick relay.
2. Railway traffic controlling apparatus comprising a railway signal adapted to display any one of four distinctive indications, a home relay controlled by traffic conditions and a distant relay controllable by other traffic conditions for controlling said signal, circuits controlled by the home relay for changing the aspect of said signal from one indication to another when the home relay is energized and to a third indication when the home and distant relays are both energized, a stick relay having a pick-up circuit arranged to be closed only when the home and distant relays are both released and a stick circuit independent thereof, circuits controlled by said stick relay when picked up for energizing said distant relay while maintaining said home relay released, and circuit means effective 70 when said distant relay and said stick relay are

both energized for causing the display of a fourth distinctive indication by said signal.

3. In combination with a railway signal for governing traffic movements over a track switch, two signal relays for governing the indications displayed by said signal, circuits controlled by said signal relays for causing the signal to display a first indication when both relays are released, to display a second indication when one relay is energized singly and to display a third indication when both relays are energized, manually controllable means for energizing said one relay in accordance with traffic conditions in a first portion of the route established by the switch which is directly in advance of the signal and for energizing the other relay when said one relay is energized in accordance with traffic conditions in a second portion of the route established by the switch which is in advance of said first portion, a stick relay manually operable when said one signal relay is released, means controlled by said stick relay for energizing said other signal relay irrespective of traffic conditions in advance of a signal provided the one signal relay is released and a route over the switch is available, and means for causing said signal to display a fourth indication when said other signal relay is energized by said stick relay.

4. In combination with a railway signal, two signal relays for controlling the indications displayed by said signal, circuits controlled by said relays for causing the signal to indicate stop when both relays are released, to indicate caution when one relay is energized and to indicate proceed when both relays are energized, manually controllable means for energizing said one relay effective only when a first section of track directly in advance of the signal is unoccupied, means controlled by said one relay when energized for energizing the other signal relay in accordance with traffic conditions in a second section of track in advance of said first section, manually operable means for energizing said other signal relay when said one relay is released due to the occupancy of said first section, and a circuit controlled jointly by said manually operable means and said other signal

relay for causing said signal to display a distinctive call-on indication when said one signal relay is released and said other signal relay is energized.

5. In combination with a railway signal, an automatic train stop having a trackway tripping member adjacent said signal and an operating mechanism which when energized retracts said tripping member to a non-operative position, two signal relays for controlling the indications displayed by said signal and for also controlling said mechanism, circuits controlled by said relays for causing the signal to indicate stop when both relays are released or when said mechanism is energized, and to indicate caution or proceed according as one or both of said signal relays are energized provided said mechanism is also energized, manually controllable means for energizing said one signal relay effective only when a first section of track directly in advance of said signal is unoccupied, means rendered effective when said one signal relay is energized for controlling the other signal relay in accordance with the condition of occupancy of a second section of track in advance of said first section, manually controllable means for energizing said other signal relay when said one signal relay is held deenergized due to the occupancy of said first track section, a circuit for energizing said mechanism closed when said one signal relay is energized, and a second circuit for energizing said mechanism including a normally open manually operable contact adjacent said signal and a front contact of said other signal relay.
